IPGentleman Intellectual Property Services, LLC(57) **CLAIM**

The ornamental design for a VR mask, as shown and described.

DESCRIPTION

FIG. 1. is a perspective view of a VR mask showing the design;

FIG. 2. is a second perspective view thereof;

FIG. 3. is a front elevation view thereof;

FIG. 4. is a rear elevation view thereof;

FIG. 5. is a left side elevation view thereof;

FIG. 6. is a right side elevation view thereof;

FIG. 7. is a top plan view thereof;

FIG. 8. is a bottom plan view thereof;

FIG. 9. is a first detail view thereof; and,

FIG. 10. is a second detail view thereof.

The dashed-dot-dashed lines depict the boundaries of the enlarged portions of the VR mask. The broken lines represent portions of the VR mask that form no part of the claimed design.
